(57) **CLAIM**

We claim the ornamental design for a tractor front cargo bed, as shown and described.

DESCRIPTION

FIG. 1 is a front perspective view of a tractor front cargo bed;

FIG. 2 is a rear perspective view thereof;

FIG. 3 is a right side view thereof;

FIG. 4 is a left side view thereof;

FIG. 5 is a front view thereof;

FIG. 6 right side rear view thereof;

FIG. 7 is a top view thereof; and,

FIG. 8 is a bottom view thereof.

The ornamental design which is claimed is shown in solid lines in the drawings. The dashed broken lines in the drawings illustrate environmental structure and form no part of the claimed design.
